ABSTRACT

A disposable french-fries accommodating container assembly includes a large container that has an upper opening and that is adapted to receive French fries, and a small container, which is fixed on an outer surface of the large container and which has an upper opening. The small container is adapted to receive seasonings and sauce.

FIG. 6

FIG. 7

FIG. 8

FIG. 9

1

**DISPOSABLE FRENCH-FRIES
ACCOMMODATING CONTAINER
ASSEMBLY WITH A FIXED SMALL
CONTAINER FOR ACCOMMODATING
SEASONINGS AND SAUCE**

BACKGROUND OF THE INVENTION

1. Field of the Invention

This invention relates to a disposable container that accommodates French fries and that is formed from a single paper sheet by folding and adhering, more particularly to a disposable container assembly, which is provided with a fixed small container for accommodating seasonings and sauce.

2. Description of the Related Art

Referring to FIG. 1, a conventional disposable container **10** is shown to be formed from a single paper sheet. The container **10** has an upper opening **11**, and a plurality fold lines **12, 13, 14**, along which the container **10** can be folded.

Because there is no means for receiving seasonings and sauce in the container **10**, a separate container is required for the same, thereby resulting in inconvenience and the likelihood of staining of fabrics, such as clothes or seat covers, by the seasonings and the sauce when eating French fries in the container **10**.

SUMMARY OF THE INVENTION

The object of this invention is to provide a disposable French-fries accommodating container assembly with a fixed small container for accommodating seasonings and sauce.

According to this invention, a disposable french-fries accommodating container assembly includes a large container that has an upper opening and that is adapted to receive French fries, and a small container, which is fixed on an outer surface of the large container and which has an upper opening. The small container is adapted to receive seasonings and sauce.

BRIEF DESCRIPTION OF THE DRAWINGS

These and other features and advantages of the invention will become apparent in the following detailed description of the preferred embodiments, with reference to the accompanying drawings, in which:

FIG. 1 is a perspective view of a conventional disposable container for accommodating French fries;

FIG. 2 is an exploded perspective view of a first preferred embodiment of a disposable French-fries accommodating container assembly according to this invention;

FIG. 3 is a stretched view of a paper sheet, which can be folded to form a large container and a small container of the first preferred embodiment;

FIG. 4 is a schematic view illustrating how the paper sheet of FIG. 3 is folded along three middle fold lines for transport and storage;

FIG. 5 is a schematic perspective view illustrating the use of the first preferred embodiment, in which sauce is received directly within the small container;

FIG. 6 is a schematic perspective view illustrating the use of the first preferred embodiment, in which sauce is received within an inverted conic plastic container that is placed within the small container;

FIG. 7 is an exploded perspective view of a second preferred embodiment of a disposable French-fries accommodating container assembly according to this invention;

2

FIG. 8 is a stretched view of a small container of the second preferred embodiment, to which two double-sided adhesive tapes are adhered; and

FIG. 9 is a schematic perspective view illustrating how a third preferred embodiment of this invention is used in a car.

DETAILED DESCRIPTION OF THE PREFERRED EMBODIMENTS

Referring to FIG. 2, a first preferred embodiment of a disposable French-fries accommodating container assembly according to this invention is shown to include a large container **20**, a small container **30** and a liquid-impermeable plastic container **40**, which is shaped as an inverted cone and which has an upper opening **41**. The large container **20** has a front wall **21**, a rear wall **22**, a bottom wall **23**, two side walls **24, 25**, and an upper opening **26**. The small container **30** has a cross-sectional area, which increases gradually from a lower end to an upper end thereof. In this embodiment, the small container **30** is shaped as an inverted pyramid, and has an upper opening **35**.

The large and small containers **20, 30** are formed integrally with each other, and are formed from a single paper sheet. Referring to FIG. 3, when stretched, the large container **20** is generally T-shaped. The front and rear walls **21, 22** extend integrally from two opposite sides of the bottom wall **23**. The side walls **24, 25** extend integrally from the front wall **21**. Two side adhesive strips **241, 251** extend respectively and integrally from the side walls **24, 25**, and are adhered to two opposite sides of the back surface of the rear wall **22**. The small container **30** extends integrally from one of the side adhesive strips **24, 25**. An auxiliary adhesive strip **31** extends integrally from the small container **30**, and is adhered to the side adhesive strip **241**. The paper sheet has a plurality of bordering fold lines **27**. Each adjacent pair of the walls **21, 22, 23, 24, 25**, the side adhesive strips **241, 251**, the auxiliary strip **31**, and the small container **30** are divided by one of the bordering fold lines **27**. Each of the bottom wall **23**, the side walls **24, 25** and the small container **30** is formed with a middle fold line **231, 242, 252, 33**, along which paper sheet can be folded into the structure shown in FIG. 4 for transport and storage. The small container **30** further has two side fold lines **34**, which define two inclined portions **36** and two abutment portions **37**. Each of the inclined portions **36** is located between the middle fold line **33** and one of the side fold lines **34**. One of the abutment portions **37** is located between one of the side fold lines **34** and the auxiliary adhesive strip **31**. The other one of the abutment portions **37** is located between the other one of the side fold lines **34** and the side adhesive strip **241**. Referring to FIG. 2, the inclined portions **36** are inclined relative to the rear wall **22**. The abutment portions **37** abut against the rear wall **22**.

Referring to FIG. 5, in use, French fries are placed within the large container **20**. Seasonings or sauce is placed directly within the small container **30**.

Referring to FIG. 6, if necessary, seasonings or sauce can be placed within the plastic container **40** that is received within the small container **30**.

FIG. 7 shows a second preferred embodiment of this invention, which includes a large container **50**, a small container **60**, two spaced double-sided adhesive tapes **70, 80** and a plastic container **90**. The large container **50** and the plastic container **90** are similar to the first embodiment in construction. Each of the double-sided adhesive tapes **70, 80** is adhered to both of the large and small containers **50, 60**.

Referring to FIG. 8, the small container **60** is formed from a single paper sheet, which has a middle fold line **61**, two

auxiliary adhesive strips **62, 63**, and two side fold lines **64, 65**. The adhesive tapes **70, 80** are adhered to the adhesive strips **62, 63**, respectively.

Referring to FIG. 9, a third preferred embodiment of a disposable container assembly **100** of this invention is shown to be hung on a window of a car, and includes a large container **110**. A rear wall of the large container **110** has a hanging hole **120** formed therethrough. A hook **200** is attached to the window by a suction cup **300**, and extends through the hanging hole **120** in the rear wall of the large container **110**, thereby hanging the container assembly **100** on the window. With this invention thus explained, it is apparent that numerous modifications and variations can be made without departing from the spirit and scope of this invention. It is therefore intended that this invention be limited only as indicated by the appended claims.

What is claimed is:

1. A disposable french-fries accommodating container assembly comprising a large container that has an upper opening and that is adapted to receive French fries, and a small container, which is fixed on an outer surface of said large container and which has an upper opening, said small container being adapted to receive seasonings and sauce, said large and small containers being formed integrally with each other, and being formed from a single sheet, said large

10 container being generally T-shared when stretched and having a front wall, a rear wall with a back surface, a bottom wall, and two side walls, said front and rear walls extending integrally from two opposite sides of said bottom wall, said side walls extending integrally from two opposite sides of said front wall, two side adhesive strips extending respectively and integrally from said side walls and being adhered to two opposite sides of said back surface of said rear wall, said small container extending integrally from one of said adhesive strips, said container assembly further including a plurality bordering fold lines, and an auxiliary adhesive strip which extends integrally from said small container and which is adhered to said one of said adhesive strips, each adjacent pair of said front wall, said rear wall, said bottom wall, said side walls, said side adhesive strips, and said auxiliary adhesive strip being divided by one of said bordering fold lines.

20 2. A disposable French-fries accommodating container assembly as claimed in claim 1, wherein each of said bottom wall, said side walls and said small container has a middle fold line, along which said paper sheet is foldable for transport and storage.
